UNITED STATES PATENT OFFICE.

SIMEON SIMONS AND ORISON SCOFIELD, OF CREEK CENTRE, NEW YORK.

LINK FOR CHAINS.

SPECIFICATION forming part of Letters Patent No. 271,141, dated January 23, 1883.

Application filed November 23, 1881. Renewed December 4, 1882. (No model.)

To all whom it may concern:

Be it known that we, SIMEON SIMONS and ORISON SCOFIELD, citizens of the United States, residing at Creek Centre, in the county 5 of Warren and State of New York, have invented certain new and useful Improvements in Links for Chains, of which the following is a specification, reference being had therein to the accompanying drawings.

This invention relates to that class of chain-links which are capable of being taken apart and readily readjusted when required for uniting the ends of a broken chain or for other like purposes; and the invention consists in the 15 construction of such links, as hereinafter more fully described, and specifically defined in the claims.

In the annexed drawings, which fully illustrate our invention, Figure 1 is a plan or side 20 view of our improved adjustable link. Fig. 2 is a view of the same with the detachable portion removed. Fig. 3 is a view of the detachable side piece and center stay. Fig. 4 is a central transverse section of the link on the line *x x* of Fig. 1, and Fig. 5 is a section on the line *y y* of Fig. 1.

Like letters indicate like parts.

The link A may be of the usual oblong form or of any other convenient form, as desired. 25 This link, as shown in Fig. 2, is formed on one side with an opening, *a*, through which passes a stay or cross piece on the detachable side bar, B. The outer surface of the severed link A on each side of the opening *a* is cut away to 35 form a T-shaped lug or bearing, *b*, which fits in a correspondingly-shaped recess, *c*, on the inner side of each end of the detachable side piece or bar, B, while the latter is provided with the three-sided rectangular lugs *dd*, which 40 fit into the spaces *e e*, surrounding the lugs formed on the link. In the center of the bar B is a projecting stud, C, which is adapted to

pass through the opening *a* in the side of the link. This stud or stay C is perforated longitudinally, and its end is flared outwardly to 45 correspond with the conformation of the body of the link. The interior of the inner end of the center stay, C, is also beveled to fit over a perforated projection or stud, D, formed on the inner side of the link opposite the opening 50 *a*. The parts thus formed are connected and rigidly secured in their relative positions by means of a tapering bolt or rivet, E, which is passed through the detachable bar B and stay-piece C into and through the stud D and side 55 of the link on which the latter is formed.

It will be seen that by means of this construction the parts of the link are firmly secured in such a manner that they may yet be readily detached when required.

Having thus described our invention, what we claim as new, and desire to secure by Letters Patent, is—

1. The combination of the severed link A, having lugs *b b*, detachable side bar, B, having stay C and recesses *c c*, and tapering bolt or rivet E, passing through perforations in the link, side bar, and stay-piece, substantially as shown and described.

2. The combination of the severed link A, 70 having perforated stud D, lugs *b b*, and spaces *e e*, detachable bar B, having perforated stay C, recess *c c*, and lugs *d d*, and the tapering bolt E, passing longitudinally through the stay-piece, substantially as shown and de- 75 scribed.

In testimony whereof we affix our signatures in presence of two witnesses.

SIMEON SIMONS.
ORISON SCOFIELD.
